Alfonso A. Banks
By his Attorney

Arthur Phelps Warren

UNITED STATES PATENT OFFICE.

ALFONSO A. BANKS, OF NEW YORK, N. Y.

TIE PRESS.

Application filed January 20, 1921. Serial No. 438,551.

To all whom it may concern:

Be it known that I, ALFONSO A. BANKS, a citizen of the United States, and resident of the borough of Manhattan, city, county, and State of New York, have invented certain new and useful Improvements in Tie Presses, of which the following is a specification.

This invention relates to improvements in tie presses and more particularly to portable devices which may be used when traveling for pressing ties and holding collar and cuff buttons as well as scarf pins and similar small articles.

15 The principal object of the present invention is to provide a simple and efficient device which may be easily and cheaply made of suitable sheet material such as celluloid, cardboard, aluminum and similar sheet metals.

Another object of the invention resides in the provision of a means for effectively securing the tie around the body of the press.

With these and other objects in view the 25 invention consists of a novel construction, combination and arrangement of parts which will be fully set forth in the following specification, claimed and illustrated in the accompanying drawings in which:—

30 Fig. 1, is a perspective view showing this improved tie press in use.

Fig. 2, is a view similar to Fig. 1 without the tie.

Fig. 3, is a longitudinal sectional view 35 through a modified form of tie press illustrating the same provided with a bottom and cover member to produce a receptacle for containing cuff and collar buttons and the like.

40 Fig. 4, is a transverse sectional view through the members and

Fig. 5, is a perspective view of the tie clamp.

Referring to the drawings in detail the 45 numeral 10 designates the body of the press comprising a tubular structure which is preferably oval in cross section and provided with a longitudinal slot 11. The ends of the body 10 are preferably rolled as at 50 12 to avoid the production of sharp edges.

The clamping means for holding the tie on the press is best illustrated in Figs. 1 and 5 and comprises an elastic strip 13 having secured to opposite ends hooks 14 and 15

which are designed to engage over the rolled 55 edges of the body 10.

In the modified form of the invention illustrated in Fig. 3, the body 10 is provided with a rigid bottom 16 and a cover 17 which is hinged as at 18 to the opposite end 60 of the body. As shown the edge of the cover is rolled to avoid the production of sharp edges and a suitable elastic strip 19 is secured at its ends to the body 10 and is substituted in this form of device for the 65 slot herein before described.

In use the one end of the tie is placed in the slot or beneath the elastic 19 according to which form of device is used and the balance of the tie is then wound around the 70 body after which the elastic clamp is secured in place by engaging the hooks 14 and 15 over the opposite ends of the body. Obviously the tie will be slightly stretched and the wrinkles and creases formed by 75 tying the same will be removed.

Should the device be used for traveling it is obvious that a structure such as is illustrated in Fig. 3 is preferable as the body of the press may be used as a container 80 for cuff and collar buttons as well as stick pins and similar small articles.

While in the foregoing there has been shown and described a preferred embodiment of this invention, it is to be understood 85 that certain minor changes in the details of construction, combination and arrangements of parts may be resorted to without departing from the spirit and scope of the invention as claimed.

What is claimed is:—

1. A tie press comprising a body upon which a neck tie may be wound and an elastic means removably associated with said body for holding the tie thereon.

2. A tie press comprising a body upon which a neck tie may be wound, said body being provided with a slot for holding the inner end of the tie firmly against the body and elastic means removably associated with 100 the body for holding the outer end of the tie against accidental displacement.

3. A tie press comprising a hollow body upon which a neck tie may be wound, said body member being provided with a slot 105 into which one end of the tie may be inserted means permanently closing one end of the body, a cover for the opposite end of

the body and means removably associated with the body for removably holding the neck tie thereon.

4. A tie press comprising a body upon which a neck tie may be wound, means for holding the inner end of the tie in contact with the body, an elastic strip adapted to

engage the outer end of the tie to hold the same against accidental displacement and hooks on the elastic strap for engagement over the edge of the body at opposite ends. 10

Signed in the city, county and State of New York, this 18th day of January, 1921.

ALFONSO A. BANKS.
